PIVOTED LOW CENTER OF GRAVITY
ANIMATED TOY

Reginald Slater, Columbus, Ohio

Application October 10, 1949, Serial No. 120,559

8 Claims. (Cl. 46—119)

1

The present invention relates in general to animated toys appropriate for use as display or amusement devices, and more particularly to animated toys having one or a plurality of figures or other type characters which are continuously activated to simulate life-like movement.

The invention is especially concerned with animated toys having elements representing human characters, or letters of a sign, or the like, particularly comical human characters, which are continuously agitated in a haphazard fashion such that their movements substantially correspond to or suggest movements of human characters, particularly in the relative movements between the several characters. The arrangement of the figures and of their associated agitating mechanisms are such as to render the device particularly appropriate for attractive window display signs and the like capable of attracting and maintaining the attention of observers and perspective shoppers and the like.

Accordingly, an object of the present invention is the provision of a mechanical toy having one or a plurality of characters adapted to exhibit animated movement, which device is of simple construction and operation, which is highly durable and substantially fool-proof in operation, and which may be produced and sold at comparatively low cost.

Another object of the present invention is the provision of a novel mechanical toy having a plurality of associated elements representing the figures of human beings, adapted to exhibit animated movements, in which the figures are so arranged and driven as to cause life-like relative movement between the figures.

Another object of the present invention is the provision of a novel mechanical toy adapted to impart life-like movement to a plurality of human simulating figures, which has a high degree of audience appeal, which is attractive in appearance, and which is particularly adaptable for use for window display and public advertising purposes.

Other objects, advantages, and capabilities of the present invention will become apparent from the following detailed description taken in conjunction with the accompanying drawings, wherein only a preferred embodiment and one modification of the invention are illustrated.

In the drawings:

Figure 1 is a front elevation of an animated mechanical toy embodying the present invention, illustrating both the figures and the driving and supporting mechanism therefor;

2

Figure 2 is a top plan view of the embodiment of the invention illustrated in Figure 1;

Figure 3 is a vertical transverse section taken through the longitudinal center of the driving and supporting mechanism along the line 3—3 of Figure 1;

Figure 4 is a side elevation of one of the animated figures, illustrating the construction of the figure;

Figure 5 is a vertical transverse section of one of the bearing spools incorporated in the construction of the animated figures, taken along the line 5—5 of Figure 4; and

Figure 6 is an exploded vertical transverse section view of the preferred form of the ball-bearing spool employed in the construction of the animated figures.

Referring to the drawings, in which like reference characters refer to corresponding parts throughout the several figures, the reference character 10 designates a rectangular base plate supporting the various components of the device, having upright supporting brackets 11 and 12 mounted thereon having sockets formed at the upper ends thereof for journaling the ends of the driving spindle or rod 13 upon which animated figures 14 and 15 are supported. The spindle 13 is preferably formed of a hollow tubular section fitted at each end with a projecting cylindrical element of smaller diameter than that of the tubular section to extend into the socket in the brackets 11 and 12.

The drive mechanism for the spindle 13 comprises an electric motor 16 of low horsepower rating, of a suitable commercially available type, mounted on the base plate 10 and coupled to a conventional commercial supply voltage source through electrical conductor 17. A manually operable switch 18 of the conventional push-button starting switch variety is coupled in series with one of the supply leads 17 and mounted on the base plate 10 to provide for manual starting and stopping of the motor 16.

The output shaft 19 of the electric motor 16 is intercoupled, through a suitable resilient belt or the like 20, to an appropriately sized pulley on an idler pulley cone 21 freely rotatable on an axle bracket 22 mounted on the base plate 10. Other axle brackets for additional pulley cones, such as the auxiliary axis bracket 23, may be mounted on the base plate 10 to provide additional stages of speed multiplication or reduction. Another pulley on the pulley cone 21 is intercoupled through a suitable resilient endless belt or the like 24 to a pulley cone 25 se-

cured to an end extension shaft 26 on the spindle 13 by means of a set screw 27. The choice of the radial diameter of the pulleys on the idler pulley cone 21 and the spindle drive pulley cone 25, which are intercoupled to the motor drive shaft 28, is made so that the speed of the spindle 13 is somewhere between the range 200 to 450 revolutions per minute for the particular electric motor employed. The spindle is rotated in a clockwise direction, as viewed in Figure 3 in the embodiment illustrated.

Suitable guard discs of greater diameter than the spindle 13 are mounted on each end of the spindle. An annular guard disc 30 movable axially along the spindle 13 is provided at the end of the spindle adjacent the upright bracket 11, the annular disc 30 being positioned by coil springs 31 secured at one end to the annular disc 30 and at the other end to a fixed mounting disc 32 coupled to the rotary spindle 13. A fixed guard disc 33 is mounted on the other end of the rotary spindle 13, and carries an inwardly extending projection 34 on the inner face thereof.

The figures 14 and 15 constituting the animated characters of the device are formed of shaped body elements representing various human figures, such as clowns, cowboys, farmers and hoboes, policemen and thieves, and the like, and are mounted on a cylindrical spool-like device, indicated generally at 35, similar to a single row radial ball-bearing. The body elements of the animated characters are mounted on a flexible strap, indicated at 36, adapted to be disposed in surrounding relation with the outer periphery of the spool 35, and is provided with snap type fasteners 37, 37' at the ends of the fabric straps to secure the figures on the spools 35, the head and foot members of the figures, indicated generally at 38 and 39, being disposed in diametrically opposed relation about the spools.

Each spool is constructed so that its outer periphery may remain stationary while the inner portion may rotate freely with the spindle 13 upon which the spools 35 are disposed in surrounding relation. The inner and outer spool elements should be provided with a substantially frictionless intercoupling, a preferred example of the construction of which is shown in detail in Figure 6. The preferred embodiment of the spool illustrated in Figure 6, indicated generally by the reference character 40, comprises an outer tubular band or ring 41 having a cylindrical outer periphery, and having a cylindrical inner bearing surface 42 centrally disposed along the inner surface of the tubular ring 41, with a projecting ledge 43 disposed at one side of the inner bearing surface 42. The radial ball-bearing element 44 comprises outer and inner coaxial ball-bearing race defining rings 45 and 46, with a ball-bearing retaining ring 47 disposed therebetween positioning ball-bearings 48. The element 44 is adapted to be disposed within the outer band 41, with the outer peripheral surface of the ring 45 bearing against the inner bearing surface 42 and abutting the inset ledge 43. A narrow bearing ridge 49, constructed in the form of a removable ring, is secured to the inner surface of the inner ring 46 and is disposed medially within the ring 46. Face plate elements 50 and 50' extending laterally outwardly from the edges of the tubular band 41 are provided, each having an annular face 51 and a truncated conical section 52, the inner end of the latter being secured to the inner ball-bearing race defining ring 46. An offset lug 53 is

secured to the annular face 51 of one of the lateral annular face elements, such as 50.

If a human type animated figure, such as shown in Figure 4, is employed, the head and arm portions, indicated at 38, are all constructed of light material, such as plastic, cork, wood or the like, and the leg and foot portions 39 are of weighted material so that the figure remains in an erect position. For example, the legs may be formed with metal rivets, such as the rivets 55 shown in Figure 4 with weighted metallic cast feet 56 secured to the bottom thereof and the legs covered with a fabric arranged in the form of the clothing of the particular character. The figures are balanced by the weighting and positioning of the head and feet of the figure, so that the principal axis of the figure is inclined slightly forwardly, when the figure is mounted on the rotary spindle 13 with the spool 35 surrounding the spindle. This is so that the figures will be rotated into an erect position during rotation of the spindle 13 due to the friction between the spool and the spindle.

An alternative form of spool which may be employed which is equally as effective to produce animated movements of the characters, but which is somewhat more expensive to produce, is illustrated in Figure 5. In this embodiment the spool is constructed of an assemblage 60, comprising an outer tubular ring or band 61, having arcuately curved recesses 62, 62' extending around the ring 61 along the inner surface at the lateral edges thereof, adapted to form a ball-bearing race with the outer concavely shaped peripheral surface 63 of the inner band or ring 64. Within the ball-bearing race, a suitable ball-bearing retaining ring 65 is disposed, positioning and spacing ball-bearings 65' about the axis of the spool. The inner ring 64 is formed with a lateral portion extending to each side of the ends of the outer ring 61, forming annular ring shaped face 66, 66'. A suitable inwardly projecting bearing ridge 67 is provided at the inner surface of the inner ring 64 which rides upon the surface of the rotary spindle 13 when the spool 60 is disposed in surrounding relation therewith. An offset lug or button 68 is secured to one of the annular lateral faces 66, 66' of the spool, similar in construction and function to the lug 53 in the spool 40.

Operation of the device is substantially as follows:

Throughout the description of the operation of the device, the form of spool employed with the figures 14 and 15 is that illustrated in Figure 6 of the drawing and referred to as the preferred form.

Upon depression of the push button starting and stopping switch 18 in the supply line 17 to the electric motor 16, the electric motor is energized, rotating the output shaft 19 to drive the spindle 13 in a clockwise direction as viewed in Figure 3, at a speed determined by the particular pulleys on the pulley cones 21 and 25 to which the resilient belts 20 and 24 are coupled. The speed of rotation of the drive shaft 19 of the motor is multiplied or reduced by appropriate selection of pulleys on the pulley cones 21 and 25 to yield a speed of rotation for the spindle 13 within the range 200 to 450 revolutions per minute.

The inner diameter of the spools 35 is somewhat greater than that of the spindle 13 so that, as the bearing ridge 49 of the spool 35 is in engagement with the upwardly disposed portion

only of the periphery of the spindle 13, rotation of the spindle 13 will impart like rotation to the inner ball-bearing race defining ring 46, and the laterally extending face plate elements 50 and 50' while the outer ring 41 is restrained from rotation by the weighted foot portion 39 of the figures 14 and 15. It will be apparent that if the plane of orientation of the spool element 35 is not exactly perpendicular to the axis of the spindle 13, the spool 35 and the figures 14, 15, coupled therewith will travel in a direction lengthwise of the spindle 13 toward the end of the spindle in the direction of which the front of the figure 14, 15 is disposed. That is to say, if the front of the figure 14, for example, is facing slightly toward the end of the spindle 13 carrying the annular disc 30 rather than facing exactly forwardly of the device, the figure will travel in that direction, as the angular relation of the portion of the bearing ridge 49 in engagement with the upper portion of the peripheral surface of the spindle 13 will correspond to a segment of a helical path about the surface of the spindle 13 rather than corresponding to a portion of a circle about the axis lying in a plane at right angles to the axis of the spindle. However, as a certain amount of friction occurs between the bearing ridge 49 of the spool 35 and the spindle 13, the figures 14, 15 will be vibrated in a somewhat pendulum-like fashion, varying the angular relation between the portion of the bearing ridge 49 engaging the surface of the spindle 13 and the axis of the spindle so that the figure moves back and forth in a jostling, bobbing, weaving motion simulating human movements and actions.

The projector lugs on the lateral faces of rotating portion of spools 35, such as the lugs 53, are provided to jostle the adjacent figure when an annular face 51 of one of the spools comes into contact with an adjacent annular face of another spool apart to prevent the spools remaining together during continued rotation of the spindle 13. The annular end disc 33 is likewise provided with a projection 34 for abruptly moving the spool away from the disc 33 when a spool 35 comes in contact therewith, and an annular disc 30 resiliently coupled through springs 31 to the fixed mounting disc 32 likewise resiliently urges the spools away from the annular disc 30 to urge the spools to remain near the longitudinal center of the spindle 13.

The resulting bobbing, weaving, jostling and shoving movements produced in the figures mounted on the spindle 13 present a very comic and amusing appearance, and stimulate great interest and audience attraction in the device. The movements imparted to the figures are particularly appropriate for comic pairs, such as a sheriff and bandit; farmer and hobo (as shown in Figure 1); policeman and drunk; a pair of tramps; and many similar comic characters. The particular choice of characters is, of course, no part of the present invention, but the particular movements imparted to the figures render the device especially entertaining when such comic characters are employed.

While only one particular embodiment and one modification of the invention have been particularly shown and described, it is distinctly understood that the invention is not limited thereto but that various modifications may be made in the invention without departing from the scope thereof, and it is desired that only such limitations shall be placed thereon as are im-

posed by the prior art and are set forth in the appended claims.

What is claimed is:

1. An animated display device comprising, a shaft journaled for rotation about a horizontal axis, driving means coupled thereto imparting rotation to said shaft, figures movably supported on said shaft, said figures each comprising a body mounted on a spool member having a freely rotatable bearing ring inwardly thereof surrounding and bearing against said shaft, the diameter of said bearing ring being substantially greater than that of said shaft to permit angular movement of said spool member relative thereto, whereby rotation of said shaft will impart irregular animated movements to said figures.
2. An animated display device comprising, a spindle having a smooth cylindrical surface journaled for rotation about a horizontal axis, driving means for imparting rotation to said spindle, a plurality of object-simulating figures movably supported on said spindle, said figures each comprising body means mounted on an outer ring member, an inner ring member having a central opening of greater diameter than that of said spindle intercoupled with said outer ring member for rotation relative thereto, and a narrow bearing ridge formed on the inner surface of said inner ring member and bearing on said spindle, whereby rotation of said spindle will impart irregular animated movements to said figures.
3. An animated display device comprising, a spindle having a smooth cylindrical surface journaled for rotation about a horizontal axis, driving means for imparting constant continuous rotation to said spindle, a plurality of object-simulating figures movably supported on said spindle, said figures each comprising body means mounted on an outer ring member, an inner ring member intercoupled with said outer ring member for rotation relative thereto, said inner ring member having a central opening and a narrow bearing ridge formed on the inner surface thereof bearing on said spindle in surrounding relation therewith, said central opening and bearing ridge being of a diameter greater than that of said spindle to permit angular movement of said ring members relative to the axis of said spindle for causing intermittent movement of the figures in the same direction and in opposite directions in an irregular animated fashion.
4. An animated display device comprising, a spindle having a smooth cylindrical surface journaled for rotation about a horizontal axis, driving means for imparting constant continuous rotation to said spindle, a plurality of figures representing human characters movably supported on said spindle, said figures each comprising a body having head and foot portions mounted on an outer ring member and having weighted means in said foot portion for maintaining said body substantially erect, an inner ring member intercoupled with said outer ring member for rotation relative thereto, said inner ring member having a central opening and a narrow bearing ridge formed on the inner surface thereof bearing on said spindle in surrounding relation therewith, said central opening and bearing ridge being of a diameter greater than that of said spindle to permit angular movement of said ring members relative to the axis of said spindle for causing intermittent movement of the figures in the same

direction and in opposite directions in an irregular animated fashion.

5. An animated display device comprising, a spindle having a smooth cylindrical surface journaled for rotation about a horizontal axis, driving means for imparting constant continuous rotation to said spindle, a plurality of figures representing human characters movably supported on said spindle, said figures each comprising a body having head and foot portions mounted on an outer ring member and having weighted means in said foot portion for maintaining said body substantially erect, an inner ring member intercoupled with said outer ring member for rotation relative thereto, said inner ring member having a central opening and a narrow bearing ridge formed on the inner surface thereof bearing on said spindle in surrounding relation therewith, said central opening and bearing ridge being of a diameter greater than that of said spindle to permit angular movement of said ring members relative to the axis of said spindle for causing intermittent movement of the figures in the same direction and in opposite directions in an irregular animated fashion, said inner ring member also having annular lateral faces forming means extending laterally therefrom of said outer ring member and having projection means thereon engaging a corresponding lateral face of the other of said figures and abruptly force the figures apart when the same come into engagement with each other on the spindle.

6. An animated display device comprising, a spindle having a smooth cylindrical surface journaled for rotation about a horizontal axis, driving means for imparting constant continuous rotation to said spindle, a plurality of figures representing human characters movably supported on said spindle, said figures each comprising a body having head and foot portions mounted on an outer ring member and having weighted means in said foot portion for maintaining said body substantially erect, an inner ring member intercoupled with said outer ring member for rotation relative thereto, said inner ring member having a central opening, a narrow bearing ridge formed on the inner surface thereof bearing on said spindle in surrounding relation therewith, said central opening and bearing ridge being of a diameter greater than that of said spindle to permit angular movement of said ring members relative to the axis of said spindle for causing intermittent movement of the figures in the same direction and in opposite directions in an irregular animated fashion, said inner ring member also having annular lateral faces forming means extending laterally therefrom of said outer ring member and having projection means thereon engaging a corresponding lateral face of the other of said figures and abruptly force the figures apart when the same come into engagement with each other on the spindle.

ment with each other on the spindle, and means secured at each end of said rotary spindle urging said figures toward the longitudinal center of said spindle when said figures come into engagement with said means.

7. An animated display device comprising, a spindle having a smooth cylindrical surface journaled for rotation about a horizontal axis, driving means for imparting constant continuous rotation to said spindle, a plurality of object-simulating figures movably supported on said spindle, a radial ball-bearing element for each of said figures, said figures each comprising body means mounted on an outer ball-bearing race defining ring of said radial ball-bearing element, the inner ball-bearing race defining ring of said radial ball-bearing element being disposed in surrounding relation with said spindle and having a narrow bearing ridge formed on the inner surface of said inner race defining ring of greater diameter than that of said spindle and bearing on said spindle, for causing intermittent movement of said figures in the same and opposite directions along said spindle on rotation of said spindle.

8. An animated display device comprising, a spindle having a smooth cylindrical surface journaled for rotation about a horizontal axis, driving means for imparting constant continuous rotation to said spindle, a plurality of figures representing human characters movably supported on said spindle, a radial ball-bearing element for each of said figures, said figures each comprising a body having head and foot portions mounted on an outer ball-bearing race defining ring member of said radial ball-bearing element, each figure having weighted means in said foot portion for maintaining said body substantially erect, the inner ball-bearing race defining ring of said radial ball-bearing element being disposed in surrounding relation with said spindle and having a narrow bearing ridge formed on the inner surface of said inner race defining ring of greater diameter than that of said spindle and bearing on said spindle, for causing intermittent movement of said figures in the same and opposite directions along said spindle on rotation of said spindle.
